UNITED STATES PATENT OFFICE.

GEORGE H. BROWN, OF POINT LOMA, CALIFORNIA.

ETCHING-MACHINE.

1,132,911.

Specification of Letters Patent.

Patented Mar. 23, 1915.

Application filed January 27, 1913. Serial No. 744,477.

To all whom it may concern:

Be it known that I, GEORGE H. BROWN, a citizen of the United States, residing at Point Loma, in the county of San Diego and State of California, have invented certain new and useful Improvements in Etching-Machines, of which the following is a specification, reference being had therein to the accompanying drawing.

10 This invention relates to etching machines and has for its object the production of a simple and efficient apparatus which will cause the desired acid to be dropped upon the plate to be acted upon.

15 Another object of this invention is the production of an etching machine which may be constructed for a minimum cost and which will prevent the acid from corroding upon the plate to be acted upon, owing to 20 the fact that the acid will be showered upon the plate in such a manner as to prevent the dross from lodging thereon.

With these and other objects in view, this invention consists of certain novel constructions, combinations and arrangements of parts, as will be hereinafter fully described and claimed.

In the drawings: Figure 1 is a perspective view of the machine. Fig. 2 is a central vertical section thereof. Fig. 3 is a detail perspective of the etching supporting tray or cradle. Fig. 4 is a side elevation partly in section of an embodiment of my invention. Fig. 5 is a detail perspective of one of the shower plates which may be used in connection with the present invention. Fig. 6 is a detail perspective of still another shower plate showing the same as being provided with a plurality of elongated apertures. Fig. 7 is a detail perspective of still another form of shower plate as being provided with a centrally located aperture. Fig. 8 is a detail perspective of the shower nozzle which may be used in connection 45 with the plate as illustrated in Fig. 7.

By referring to the drawings by numerals it will be seen that 1 designates the body of the machine which may be formed of any shape or design desired and may also be 50 formed of any desired material which will resist the chemical action of the acid contained within the interior of the machine. This body 1 is supported upon parallel frames or standards 2 and is pivotally mounted thereon by means of journal pins 3

which are secured to the side of the body 1. A plurality of handles 4 are secured to the sides of the body to facilitate the swinging of the body. This body is provided upon its ends with a stop lug 5 which lug is adapted to fit in the socket 6 formed in the outer end of the locking pawl or clamp 7. These locking pawls or clamps are pivotally secured to the floor by means of journals 8 and are yieldably supported at their outer ends by 60 means of coil springs 9. It will be seen that as one of these lugs 5 engage the locking pawl or clamp 7 in the manner as illustrated in Figs. 1 and 2, the body 1 will be held in a set position. A locking arm 10 is carried by one side of the body 1 as illustrated in Figs. 1 and 2, and is provided with a rounded lower end 11 which rounded lower end is adapted to engage the socket 6 carried by the clamp 7 for holding the body 75 1 in a horizontal position.

The body 1 is provided with a door 12 so that access may be had to the interior of the body, and a tray or cradle 13 is supported therein by means of the pivot members 14. These pivot members 14 are pivotally secured to the interior of the body 1 and have enlarged ends 15 which ends normally prevent the eyes 16 of the side frames 17 from becoming accidentally detached 80 therefrom. These pivot members 14 are preferably formed of rubber or other similar material. The frames 17 carry at their lower end a plate 18 which plate is provided with a plurality of apertures 19 and 85 a plurality of upwardly extending lugs 20, which lugs constitute means for holding the plate adapted to be worked upon by the acid against displacement from the cradle. These frames 17 engage the plate 18 at its 95 corners so as to constitute an efficient support, and prevent the plate from tilting relative to the frame.

Compartments 21 and 22 are formed at opposite ends of the body 1 and are adapted to receive or contain the desired acid for the purpose of etching the plate. It will, therefore, be seen that owing to the fact that the compartment is carried at each end of the body, one compartment will be 100 filled as the other is emptied. Each compartment 21 and 22 is provided with a bottom 23 which bottom comprises a pair of plates converging toward their inner ends as indicated at 24 and terminate in a chan- 110

nel portion 25 for receiving one edge of the spraying plate 26. It will be seen that owing to the fact that the plates constituting the bottom 23 converge toward their inner ends, an inclined bottom will be produced both upon the inside and outside of the compartments 21 and 22 thereby facilitating the draining of the compartment while the liquid or acid is running out of the compartment and also facilitating the filling of the compartment while the acid is running into one of the compartments 21 or 22. The opposite side of the plate 26 is supported by a channel 27 and an inlet tube 28 is formed in each compartment 21 and 22 for facilitating the entrance of liquid into the compartment other than through the apertures formed in the perforated or spraying plate 26. It should be understood that the tube 28 as well as the other portions of the device may be made of glass or other non-corrodible material.

The cradle 13 is supported within the body 1 in such a position as to be in direct alignment with the spraying plates 26 carried by the several compartments 21 and 22 so that the acid discharged from the compartments will be directed upon the plate adapted to be acted upon by the acid. It, of course, should be understood that as one compartment has been emptied and it is desired to further act upon the plate or etching the body 1 is swung in the direction of the arrow upon its pivot thereby causing the acid from the opposite tank to drop or fall upon the cradle 13. Of course, the body 1 while so swinging will be entirely inverted so as to have the compartments 21 and 22 in a reversed position from that as illustrated in Figs. 1 and 2.

A false bottom 29 is supported within the body 1 and an outlet valve or port 30 is carried by the false bottom 29 so as to allow the washing of the plate to be etched. An outlet opening 31 is also formed in the body and is normally closed by means of a plug 32, and it should be understood that by moving this plug the body may be drained through the opening 31. As illustrated in Fig. 6 the spray plate 26 may be provided with a plurality of elongated apertures 33 for facilitating the discharge of acid from the tanks 21 and 22. A plate, as illustrated in Fig. 7, may also be used, which plate is provided with a centrally located aperture 34 for receiving a spraying nozzle 35.

From the foregoing description it will be seen that by use of the present device it will not be necessary to employ brushes or other apparatus to keep the surface of the zinc or other metal free from insoluble deposits caused by the action of the acid. It, of course, should be understood that this deposit would interfere with the action of the acid and unless these substances are re-

moved in some manner, it would be impossible to make practical or serviceable line-cuts or etchings. It will be further understood that owing to the length of the fall of the acid which is produced in the machine above described, the acid will strike the plate with sufficient force to remove the insoluble material and produce perfect work. Sufficient acid may be stored in one of these tanks of the machine to complete one "bite" or etch and the machine need not be reversed until the plate is ready for the second "bite" or etch. If it is desired to continue the first "bite" longer than is possible by the amount of material in one of the tanks, the machine may be inverted instantly and the process continued indefinitely. The machine is so constructed that there is no need for the fumes of the acid to escape while producing the etching.

From the foregoing description it will be seen that a very simple and durable device has been produced which may be very cheaply constructed and will perform the necessary results for producing a clear line-cut or etching thereon.

As illustrated in Fig. 4, I have shown an embodiment of the invention wherein the body 1^a is formed on a slightly different design having extending ends 2^a. Stop lugs 3^a are formed adjacent the extending end 2^a and are adapted to engage the clamp or latch 4^a as illustrated in Fig. 1. The body 1^a is also provided with a centrally located arm 5^a which may be also brought into engagement with the clamp 4^a to hold the body 1^a in a horizontal position. A cradle 34 is supported within the body similar to the cradle 13 in the embodiment above described, and this cradle is supported by means of the bracket 35. The whole body 1^a is supported upon the side frames 36 and are pivotally secured thereto by means of the pivot pins 37. The interior of the machine as illustrated in Fig. 4 may be formed of the same construction as illustrated in Figs. 1 and 2. A false bottom 38 is supported within the body 1^a and a drain nozzle 39 is carried within the body and constitutes a water drain for the body to allow the escapement of water therefrom.

From the foregoing description, it will be seen that a very efficient and durable device has been produced for causing the acid within the etching machine to be discharged in a spray upon the zinc plate or device to be acted upon with sufficient force to obtain the desired result. It should be further understood that by having the reversible structure as set forth, the action of the acid may be made substantially continuous owing to the fact that the body of the device may be so rotated as to cause the acid to be used a number of times.

It should be understood that the false bot-

toms 29 and 38, as indicated in Figs. 2 and 4 respectively, are for the purpose of allowing the use of fresh water on the surface of the plate being etched so as to clean the 5 same of acid before removing the plate from the cradle. It will be seen that the water so used will pass directly out of the port without becoming mixed with any other chemicals which may have become spilled from 10 the tanks during the process of inverting. As will be seen by considering the drawings, all the bolts which project within the interior of the body of the machine are protected from the acid by means of the insulating protectors.

Having thus described the invention, what is claimed as new, is:—

1. An etching machine of the class described comprising a support, a body rotatably mounted therein, tanks carried by the ends of said body, means formed in said tanks for discharging the liquid from one end of the end walls thereof, and a plate support carried within said body.
2. A machine of the class described comprising a support, a body rotatably mounted therein, tanks carried by the opposite ends of said body, means for discharging liquid from one end of the end walls thereof, a plate support carried within said body and being placed in alinement with said liquid discharge means formed in said tank, and means engaging said body for holding the same in the desired position.
3. A machine of the class described comprising a support, a body rotatably mounted therein, tanks carried by the ends of said body, means formed in said tanks for allowing the discharge of liquid therefrom, and a plate support pivotally secured within said body and capable of being swung therein for causing the plate to be held in the path-way of said discharge means formed in said tanks.
4. A machine of the class described comprising a support, a body rotatably mounted therein, tanks carried by the opposite ends of said body, said tanks provided with inclined end walls for directing liquid into 50 one end of said tanks, said tanks provided with liquid discharge means, and a plate support pivotally secured within said body and capable of being swung in the path-way of said discharge means formed in said 55 tank, and means carried by said body for holding the same in a set position.

5. A machine of the class described comprising a support, a body rotatably mounted therein, tanks carried by opposite portions of said body, spraying means carried by said tanks, a plate support pivotally secured within said body and adapted to be placed in alinement with said spraying means for causing the acid contained within the tank to be discharged directly thereon, and an inlet tube carried by each tank for facilitating the entrance of acid therein. 60 65

6. A machine of the class described comprising a body, said body provided with a plurality of tanks, a plate supporting cradle, pivot members pivotally secured to said body, each pivot member provided with an enlarged end, said cradle comprising a plurality of frames having eyes formed at their upper ends, said pivot members passing 70 through said eyes and pivotally connecting said cradle to said body, a plate support carried by said frames, said plate support provided with a plurality of drain apertures, and a plurality of lugs formed around 75 the edge of said plate for preventing the accidental dropping of work from said plate.

7. A machine of the class described comprising a support, a body rotatably mounted therein, lugs carried by said body, means 80 engaging said lugs for holding the body in a set position, acid containing tanks carried by said body, said tanks provided with acid discharge means in one end of their end walls, and a plate support carried within 85 said body and placed in alinement with said acid discharge means for allowing the acid in said tanks to be discharged upon said plate support.

8. A machine of the class described comprising a body, acid tanks carried thereby, a plate support carried within said body, acid discharge means formed in said tanks and adapted to discharge acid upon said support, a false bottom carried within said 90 body, drain means carried by said false bottom, and said body provided with an outlet discharge opening formed therein, and means engaging said outlet discharge aperture for normally closing the same. 95 100 105

In testimony whereof I hereunto affix my signature in presence of two witnesses.
